MULTIPLE CIRCUIT PROPORTIONAL
CONTROL SYSTEM

Alan Stewart Fitz Gerald, Wynnewood, Pa.

Application June 27, 1933, Serial No. 677,788

17 Claims. (Cl. 175—312)

This invention relates to methods of controlling, in a coordinated manner, a plurality of electric load units by means of saturating reactor arrangements such as, for example, apparatus of the general type I have described in my copending application entitled Magnetic amplifiers, filed in the United States Patent Office June 21, 1933, and bearing Serial No. 676,785.

It is especially adapted to the control of illuminating arrangements such as are required in providing spectacular effects for theatre stage presentations, external decorative lighting and like purposes. It is, however, not restricted to the control of illumination only and may be used with advantage for such purposes as the control of motors driving textile machinery, paper-making equipment, wire and rope-winding devices and similar applications.

The main object of the invention is to provide a means of concentrating, into a relatively compact control board, all of the switching and control elements necessary for the control, both severally and in combination, of the intensity of illumination of a relatively large number of illuminating units.

When such complex and extensive lighting systems are controlled by means of switchboards of the usual type, for manual operation directly, such switchboards may be many feet in length and may require considerable mobility on the part of the operator. They may, in many cases, require a number of operators in order to produce elaborate lighting effects requiring rapid changing of illumination.

In some prior systems, it has been possible to provide a control panel so compact in dimensions that all of the control elements for a large stage may conveniently be reached by a single operator without moving from a stationary position. Equipments of this type, which may resemble an organ console, rather than an electric switchboard, may be situated at a control station located in the house or auditorium, whereby the operator may directly observe the effects he is producing.

In the case of prior systems, however, this result has been achieved by making use of the grid control feature of vacuum tubes or space discharge devices. It is well-known that with such devices relatively large amounts of power may be controlled with nicety by applying to the grids of the space discharge devices, very limited amounts of power. Obviously, this property renders it readily possible to employ control elements of small dimensions. Thus, a large number

of such control elements can be provided in a restricted space, as desired.

It is, however, a very definite disadvantage of such prior systems that the space discharge devices are not only expensive in first cost but have a very limited life. Thus, they must be replaced at frequent intervals. Not only does this involve the expense of renewal of these devices but, in addition, it is necessary frequently to test the apparatus so that worn-out tubes may be detected and replaced without involving interference with performances.

It is an object of the present invention to provide a control system which will accomplish, without the necessity of employing space discharge devices, all of the objects hitherto achievable, only, where such devices have been used.

It is a further object of the invention to provide an improved control system which shall consist only of apparatus of well-known, simple and reliable form, which is substantially more durable in its characteristics than any space discharge devices hitherto available, and which has a minimum of mechanical apparatus and moving parts.

It is a still further object of the invention to provide a system having great flexibility in adaptation to diverse requirements and which, at the same time, requires only a very limited number of types of apparatus whereby a high degree of standardization in manufacture is possible.

It is yet another object of the invention to provide a system which does not require polyphase power, which is not affected by fluctuations in the supply frequency, and which is more economical than arrangements involving space discharge devices, in that no power is consumed in the heating of electrodes, and in which the circuits are more simple, in that no cathode heating circuits are necessary.

The basic feature of the invention is indicated by the following considerations, referring to lighting control systems of the general type described.

Space discharge devices of the grid control type can, as is well-known, readily be controlled by means of extremely small amounts of power, representing, in many cases, very minute fractions of a watt. On the other hand, any simple manual control device, sufficiently small so that a large number of them may be mounted in a limited space, yet, on the other hand, sufficiently large to be conveniently manipulated by the human hand, can easily control amounts of power exceeding several voltamperes.

There is, therefore, nothing to be gained by the

use of devices so sensitive that they may be controlled by minute amounts of power. It is, in fact, uneconomical to employ expensive and short-lived devices of this type, if it can be shown that they are not essential to the result achieved. In view of the fact that a simple manual control device can furnish a controllable output many hundred times greater than the minimum power necessary to control, by means of the grid, 5 a space discharge device, the invention provides a system of control in which the energy furnished by the control device is more efficiently made use of, and is directly employed to actuate the control system, without the use of a space discharge 10 device as an intermediary.

The control element may consist of any suitable electric translating or variable output alternating current device, either of electro-magnetic or other convenient type. It is preferred to employ 20 a simple electromagnetic device of the form embodying relatively movable primary and secondary windings such as is exemplified by a miniature single-phase induction regulator. With this form of construction, the output is a fixed 25 function of the position of the movable elements. It has also the advantages, as compared with variable resistors and the like, that all windings may be insulated and embedded so as to be immune from atmospheric corrosion, and that sliding 30 or open contacts are avoided.

All of the above devices may readily be furnished in inexpensive and reliable form capable of indefinitely long life in comparison with space discharge devices.

35 A feature of the invention consists in the fact that proportional control may be obtained by employing a plurality of saturating reactors with common excitation. A further feature resides in the use of saturating reactors and rectifiers connected to form a catenated system in accordance 40 with the magnetic amplifying arrangements disclosed in my co-pending application, filed June 21, 1933, and bearing Serial No. 676,785.

A further feature consists in the use of an alternative switching arrangement whereby a saturating reactor may be used either in series or in parallel with a control element, whereby the action may, at will, be made either direct or inverse, without the use of any mechanical reversing gears or motions, such as have hitherto been 50 used in the art.

A still further feature consists in the employment of a compensating winding on the second stage reactor, as disclosed in my co-pending application cited, whereby the effect of the magnetizing current of the first stage reactor, when no saturating effect is applied thereto, is nullified.

These and other novel features which I believe 60 to be characteristic of my invention will be set forth with particularity in the appended claims. My invention itself, however, both as to its organization and method of operation, together with further objects and advantages thereof, may best be understood with reference to the following description taken in connection with the accompanying drawings, in which

Figure 1 is a general diagrammatic view of an embodiment of my invention; and

Fig. 2 is a diagrammatic view showing, in 70 greater detail, a portion of the embodiment of my invention shown in Fig. 1.

In Fig. 1 I show a typical stage lighting system of the type including "grand master" control, "color master" controls and a further number 75 of individually controllable units.

In Fig. 1 I show an illuminating circuit 1 which may be, for example, a footlight, border, or pocket, etc. circuit. The circuit 1 is energized from an alternating current source 2 in series with the reactance winding 3 of a saturating reactor 4 having a core 5 and direct current saturating winding 6. The winding 6 is supplied with rectified current by means of a rectifier 7. The rectifier 7 is energized also from the alternating current source 2 and is connected in series with a second saturating reactor 8 energized through the rectifier 9 from the control element 10 in accordance with the method of connecting saturating reactors and rectifiers in catenation for the purpose of providing an amplifying effect which is shown and described in my co-pending application filed June 21, 1933, bearing Serial No. 676,785.

The saturating reactor 8 may be similar to the reactor 4 but may be of substantially smaller rating and dimensions. In order to simplify the drawings, the cores of the reactor 8 and other reactors to be later described are omitted, only the windings being indicated. The reactor 8 has a reactance winding 11 which is connected in series with the rectifier 7 and direct current saturating winding 12 energized from the rectifier 9.

The control element 10 has input terminals 16 and output connections 17, the latter being connected to the rectifier 9, as shown. The rectifier 9 may be similar to the rectifier 7, but may be of substantially smaller rating and dimensions.

The control element 10, being in effect a miniature induction regulator, will furnish energy at the output 17 which will be proportional to the voltage impressed on the terminals 16 and will vary in accordance with the position of its movable portion which latter may be adjusted by means of the knob 18.

If it be assumed, for the moment, that the terminals 16 of the control element 10 are connected to a source of fixed alternating current voltage, the action of the control circuit will be as follows. By movement of the knob 18, the output energy from 10 at the output terminals 17 may be varied from zero to a maximum. Thus, the energization of the rectifier 9 may be varied in like degree. Accordingly, the rectified current furnished to the saturating reactor 8 will likewise be controlled by manual adjustment of the knob 18. The degree of saturation of the reactor 8 will, therefore, be varied and the impedance of the reactance winding 11 will undergo a corresponding change. This will cause the energization of the rectifier 7 to vary in the same way which, in turn, through the saturation of the larger saturating reactor 4, will control the intensity of the illumination of the circuit 1.

The control element 10 is arranged to be energized, by means of a switch 19, either directly from the source 2 or, alternatively, in series with a further saturating reactor 20 having saturating winding 21 and the reactance winding 22. The switch 19 has three positions shown as 23, 24, 25. In position 23 the control element is connected directly to the source 2. In position 24 it is disconnected and deenergized. In position 25 the control element is connected in series with the reactance winding 22 of reactor 20 across the source 2.

It will be apparent that the energization of the control element 10, if the switch 19 is in position 25, will depend on the saturation of reactor 20. Thus, the illumination of 1 will be jointly con-

trolled by the position of the knob 18 and the degree of saturation of the reactor 20.

Thus, if it is desired to have individual and independent control of the lighting circuit 1, the switch 19 is placed in position 23. On the other hand, when it is desired to control 1 in accumulation with other units, the whole to be simultaneously controlled as a group unit, the switch 19 is placed at 25. Under this condition, if the position of 10 is such as to give maximum output the brilliancy of the lights will be controllable from zero to a maximum, in conjunction with other groups according to the saturation of the reactor 20. If, on the other hand, 10 is adjusted to some intermediate position, the lights will be proportionally controlled, in coordination with the other accumulated units, from zero to an intensity somewhat less than the maximum, corresponding to the position of 10. This proportional dimming feature is an important result achieved by means of the invention.

In a full-size stage equipment, there will, of course, be a considerable number of lighting circuits, each controlled by means of individual control elements 10. Three control units are shown in the drawing, but it is to be understood that the invention contemplates any desired number of circuits. For the sake of clearness, and to simplify the drawings, details of the additional circuits have been omitted since these may be identical in arrangement with the one shown, each consisting of rectifiers 7 and 9, reactors 4 and 8, and the load circuit 1.

An important feature of means for group control of a number of units which must be considered is the fact that the method of control employed must be operable with an indeterminate number of circuits 1 accumulated into a group. The system must function in the same manner whether only one or two such units are accumulated, or whether substantially all of the units are operated together. The invention provides this feature in the following manner.

Each control unit 10 is provided with an individual control reactor 20, as shown. All of the saturating windings 21 of reactors 20 are connected to form a common circuit. The drawings show these windings connected all in series, but it will be apparent to those skilled in the art that they may be connected in parallel or in such series-parallel grouping, as may be convenient. Since the drawings only show three control elements 10, whereas a larger number is contemplated, there are shown open connections in the common circuit of the saturating windings 21 which may be supposed to represent connections to these additional circuits.

All of the saturating windings 21 are energized from a rectifier 70. This may approximate in order of magnitude, in some cases, to that of the rectifier 7, where there are a large number of circuits to be controlled. In other cases, it may be of smaller rating than 7. The rectifier 70 is energized from the source 2 in series with a saturating reactor 80, which may be of the same type as the reactor 8 having, likewise, a saturating winding 120 and a reactance winding 110. Similarly, the reactor 80 is furnished with saturating current from the rectifier 90 which is controlled by the control element 100. The rectifier 90 may be similar to 9 and the joint action of 100, 90, 80 and 70 may be in accordance with the operation of 10, 9, 8 and 7. The control element 100 may be identical in construction with the device 10 and may, in the general lighting control sys-

tem, represent what is known as one of the "color master" controls. That is to say, the three control elements 100 may represent the white, red and blue color masters, this being a representative arrangement.

It will be realized that control element 100 varies the direct current energization of all of the reactors 20 in exactly the same manner as the control element 10 controls the saturating current of the reactor 4. The operation of 100 will, however, control the alternating current energization of such of the control elements 10 as may be set with switches 19 in position 25. All elements 10 so connected will be controlled in unison by the color master 100. Such control elements 10 as are connected directly to the source 2 by means of switch 19 being placed in position 23 will remain entirely unaffected by the operation of the color master.

Such of the circuits 1 as are not required may be set at zero illumination by operating the several switches 19 to position 24. It will be appreciated that since each control element 10 has an individual control reactor 20 the action of the group control system will be entirely unaffected by the number of units which are accumulated under any given color master. Saturating reactors of the type commonly employed in systems of this general class are usually so constructed that mutual inductance between reactance and saturating windings is eliminated. Thus, the current in the windings 21 is entirely independent of the position of the switches 19.

While in the drawings only one complete system of connections from the output of the control element 100 to the saturating windings 21 is shown, it will be understood that each color master is likewise connected to its appropriate group of color units.

Each of the color masters 100 is energized from the source 2, either directly or in series with individual reactors 200, which are similar in function and may be similar in type to the reactors 20. A selector switch 190 has the same function and operation as the switch 19 and enables the color masters to be operated individually by direct connection to the source 2 or to be accumulated and controlled simultaneously by the grand master 1000. This result is accomplished in a similar manner to the collective control of the control elements 10 by one of the color masters 100, the reactors 200 being excited by a common circuit embracing the saturating windings 210 from a rectifier 900 which may be similar to the rectifiers 9 and 90.

Since, in general, the color masters will not usually exceed three or four in number, a single stage of rectifier control will probably be sufficient to furnish the amount of saturating power required. But, it will be obvious to those skilled in the art that, if desired, a catenated arrangement exactly like the method employed for controlling the control elements 10 from the color masters 100, embodying reactors 20 and 80, and rectifiers 70 and 90, may be employed.

I have shown in Fig. 1 a general diagrammatic view of an embodiment of my invention showing how the complete arrangement of individual circuits, color groups, etc. may be controlled either individually, through the color masters, or through the grand master control element.

There may also be included in the arrangement shown in Fig. 1 various detail features of my invention which it is inconvenient, for reasons of space, to show in Fig. 1. These details I show

in Fig. 2 which is a diagrammatic view of a portion of the arrangement shown in Fig. 1.

Figure 2 shows detail control arrangements relating to a single circuit, in which the illuminating circuit 1, power source 2, saturating reactor 4, rectifiers 7, 9 and 70, and saturating reactors 8 and 20, are all as shown in Fig. 1.

Special features of my invention which are shown in Fig. 2 are: the method by means of which my invention provides for pre-selection of illuminating effects whereby the illumination for a subsequent scene can be set up in advance of the presentation thereof, while the previous scene is in progress; and, the method of producing inverse action whereby one circuit can be increased in intensity, while another circuit may be decreased in intensity, simultaneously, when both are operated from a single group control.

In Figure 2 I show also additional windings 13 and 130 on saturating reactors 4 and 20, respectively. These windings are wound co-axially with the saturating windings 6 and 21, respectively, and are energized with direct current from a source 14, preferably another rectifier. The windings 13 and 130 are connected so as to oppose the saturating effect of windings 6 and 21, and the excitation furnished by these windings is arranged to be substantially equal and in opposition to the excitation present in the windings 6 and 21 when there is no saturating effect applied to the saturating reactors 8 and 80, respectively. The windings 13 and 130 are for the purpose of compensating for the magnetizing current of 8 and 80 in accordance with the method described in my copending application, filed June 21, 1933, bearing Serial No. 676,785.

In view of the fact that the embodiment of my invention shown in the drawings requires only two stages of amplification and relates more particularly to the control of illumination, the compensating windings 13 and 130 may, if desired, be omitted. The illumination of most types of electric lamps is reduced substantially to zero when the current in the lamps is reduced to approximately fifty per cent. of the normal rated current. However, the compensating windings provide an increased range of control and may be advantageous in certain instances.

In Figure 2 I have shown the power source 2 having three conductors 201, 202, 203, for the purpose of making available two different voltages for operating the control system. For example, there may be provided between conductors 201 and 203 the full voltage across which the lighting load is to be operated and which may, for example, be 110 volts, alternating current. Between conductors 201 and 202 I provide a lower voltage, also alternating, which may be of the order of 20 volts.

In view of the fact that my system preferably employs rectifiers of the contact type, it may be convenient to provide this lower voltage since contact rectifiers can, at the present time, more readily be procured for such lower voltages.

In modern stage-lighting systems, it is customary to provide what is known as "pre-selection" of the illumination for one or more entire scenes in advance of any scene actually being presented. On the conclusion of the current scene, the lighting effects for the next scene, which may be of a complex character, and may differ widely from the effects in the scene which precedes it, may instantly be reproduced, in accordance with prearranged plan, by operating a single switch, known as the "all master" instead

of it being necessary individually to manipulate all of the control elements 10 which are involved, each being adjusted to the intensity required in the next scene.

My invention is readily adapted to the provision of this "pre-selecting" feature.

In Figure 2 I show the control element 10 and reactors 20 in duplicate, and designated 10a, 10b and 20a, 20b, respectively, in order to provide the pre-selecting feature. As shown in Fig. 2, 10 the output connections 17a and 17b, of the control elements 10a and 10b, may be connected, alternatively, to the rectifier 9 by means of scene-changing relays 26a and 26b having contacts 27a and 27b, respectively. The operating coils 28a 15 and 28b of the scene-changing relays are energized, respectively, from conductors 30, 31A and 30, 31B. By means of a selector switch 32 having contacts A and B, as well as an "off" position, either 31A or 31B may alternatively be energized at will. The switch 32 is known to those skilled in the art as the "all master."

Although but a single pair of scene-changing relays 26a and 26b are shown in the drawings, it is to be understood that there will be a similar pair for each individual illuminating circuit in the entire system, as indicated by the open-end conductors 30, 31A and 30, 31B, and all of these relays are intended to be simultaneously operated by the switch 32.

Thus, if, in Fig. 2, the switch 32 be closed on contact A, energizing the conductor 31A, scene-changing relay 26a will be energized, closing its contact 27a. Thus, the control element 10a is connected to the rectifier 9 and the control element 10b is disconnected. Thus, the illumination of circuit 1 is controlled through the control element 10a, either independently, or by group control, under the color master or the grand master, in accordance with the position 40 of the switches 19, 190.

In a similar manner, if the all-master switch 32 be closed onto contact B, the circuit 1 will be controlled through control element 10b and 10a will be disconnected.

It will be obvious to those skilled in the art that not only the individual circuit control elements 10 but, in addition, the color masters 100 and even the grand master 1000 as well, may, if desired, be likewise duplicated and pre-selected by means of a like number of additional scene-changing relays 26a and 26b, all operated from the conductors 30, 31A and 31b, and controlled by the all-master switch 32.

It will be further appreciated that more than two scenes may be pre-set if desired, by providing, instead of only two control elements, scene-changing relays, and contacts on the all-master switch 32, three or more, per circuit, as may be required.

In the presentation of illuminating effects of theatre stages and the like, it is frequently required that two or more lighting circuits be controlled in contrary sense. That is, it is desired, simultaneously, to cause one circuit to increase and a second circuit to decrease. Such a requirement, for example, is involved in producing "sunrise" and other similar effects. This result is readily brought about by means of another feature of my invention which I show in Fig. 2.

In accordance with the prior art, it has been the custom to secure this result through the use of mechanical reversing gears or motions. By means of the improved system shown in Fig. 2,

1 secure the desired reversing action entirely through electrical means.

5 In Figure 2, the control elements 10a and 10b are each shown capable of being connected to the power source, either directly, for independent control action, or in series with the reactance winding 22 of the saturating reactors 20, when group control is desired, exactly as shown in Fig. 1, by means of switches 19a and 19b.

10 In Figure 2, I show double pole switches 33a and 33b, whereby the connection of the control elements 10a and 10b may be modified. On referring to Fig. 2 it will be observed that when the double pole switches 33a and 33b are placed 15 in the left-hand position, the connection of the control elements 10a and 10b is as shown in Fig. 1. With this connection, the control will be direct. That is to say, when one of the circuits is accumulated on to one of the color masters, 20 when the color master is turned so as to increase the energization of the rectifier 90, the rectifier 70 and the saturating winding 21 of the reactors 20, the energization of the input terminals 16 of the control element 10 will likewise be increased, 25 and the illumination of the circuit 1 will be increased directly as the color master 100 is increased.

If, on the other hand, the double pole switch 33 is placed in the right-hand position, the connection of the control elements 10 is modified 30 as follows. Instead of the control elements 10 being energized in series with the reactance winding 22 across the low-voltage supply conductors 201 and 202, the connection is now such that the 35 input terminals 16 of the control elements 10 are connected in parallel with the reactance winding 22, and the control element and reactance winding, so connected in parallel, are energized from the high-voltage power conductor 201 and 203 in series with an impedance of fixed 40 value 34 which, for example, may be a small choke coil.

Since the control element and reactance winding, in parallel, are now connected across a higher voltage, it will be appreciated that the current drawn from the source conductors 201, 203, will 45 be essentially determined by the impedance 34. In other words, the control element 10 and the reactance winding 22, jointly, will be energized 50 with a substantially constant current. Thus, when the saturating reactor 20 is completely unsaturated and the impedance, represented by the reactance winding 22, is relatively high, the control element 10 will be energized at substantially 55 the same power input as would be the case when the terminals 16 are directly connected to the power source conductors 201, 202, through contact 23.

If now, the saturating reactor 20 be saturated 60 by current from the rectifier 70, the impedance of the winding 22 will be lowered and a portion of the current flowing through the choke coil 34 will be diverted from 10, which will accordingly be energized to a reduced extent. When the 65 maximum saturating effect is applied to 20 and the impedance of 22 is very low, substantially all of the current flowing through 34 flows through 22 and the control element 10 is substantially deenergized.

70 It will thus be observed that when the switch 33 is placed in the right-hand position, the effect 75 of the color master 100, upon the control element 10 and the circuit 1 thereby controlled, is inverse. When the color master 100 is increased to a maxi-

creased substantially to zero, and when the color master is adjusted to a minimum position, the energization of control element 10 and the circuit 1 connected thereto will be a maximum. It will, therefore, be noted that if two different lighting circuits be accumulated on to one of the color masters 100, and if one of these has the switch 33 placed in the left-hand position, and the second has the switch 33 placed in the right-hand position, the first-mentioned circuit will be directly controlled by the color master and the second-mentioned circuit will be inversely controlled by the same color master. In other words, as the color master is increased from zero to a maximum, the first-mentioned circuit will likewise be increased from zero to a maximum, but the second-mentioned circuit will be decreased from a maximum to zero.

It is also to be noted that under both of these conditions, proportional dimming of each individual circuit, through the individual control element 10, is still furnished. If the control element 10 be adjusted so as to give one-half brilliance, then, when accumulated on to one of the color masters, the intensity of the light, when 25 the color master is varied from zero to a maximum, will either vary from zero to half brilliance or from half brilliance to zero, according to whether the connection is for direct or for inverse action, in accordance with the position of the switch 33.

While I have shown in Fig. 2 the reversing action by means of the changeover switch 33 applied to an individual lighting circuit, I wish it to be clearly understood that exactly the same connection is to be applied in precisely like manner to the color master control element 100. Thus, by means of the inverse action so obtained, all of the white lights, for example, accumulated on to the white color master, may be decreased at the same time that all of the red lights, accumulated on to the red color master, may be increased simultaneously at one operation of the grand master 1000.

While my invention is not to be limited to any specific arrangement or to any exact type of size of control elements, rectifiers or reactors, the value and utility of the invention may be better illustrated, if reference be made briefly, to apparatus which was employed in a specific embodiment of the invention which has been studied.

It is well-known to those skilled in the art that saturating reactors of the type generally employed in systems of the general class referred to in this specification usually require from two to five per cent. of the power output rating, to be furnished to the saturating winding in order to control the load circuit within the desired limits. For example, if the circuit 1 represents a 1 kw. load, the direct current power required to be furnished to the saturating winding 6 of the reactor 4 will be of the order of 50 watts or less. The output of 7 will, therefore, be about 50 watts and, since the efficiency of a rectifier of the type contemplated will be approximately 50 per cent., the amount of alternating current input to be supplied to the rectifier 7 will be in the neighborhood of 100 volt-amperes, which amount of power the reactor 8 should control.

On this basis, the direct current input to the reactor 8 would be 5 watts and the alternating current input to the rectifier 9 will be of the order of 10 volt-amperes. The control element 10, therefore, should be capable of furnishing an alternating current output variable from zero to 10 75

volt-amperes. This figure, however, is a conservative one and if the reactors be specially designed, substantially less than five volt-amperes output, from the control element 10, may be sufficient.

The reactors 20, since each has only to control the input to the control element 10, which is not likely to exceed 20 volt-amperes, may be even less in rating and dimensions than the reactors 8.

10 However, for reasons of standardization, it may be desirable to build these of the same core dimensions as the reactors 8.

As indicated in the specification, according to the number of control elements 10, which are to be controlled by the color master, the rating of the rectifier 70 may be similar to that of 7; that is to say, it may furnish an output of 50 watts or less, as may be necessary. Likewise, the reactor 80 and the rectifier 90 may be similar in rating to 20 the corresponding devices 8 and 9.

Similarly, reactors 200 may be of the same rating as reactors 20 and rectifier 900 similar to 9 and 90.

All of the control elements 10, 100 and 1000 may be of identical construction. I have found that the frame size and core punchings, such as may be used for the smallest size of fan or fractional horse-power motor, are very suitable for forming the basis of the construction of the control elements. While the torque exerted on the movable element of the control device, when an output of 10 volt-amperes is drawn from the secondary, can be discerned when manually adjusting the knob 18, it is not such as to impede or substantially affect the action of the device. Suitable locking means, however, such as a friction or serrated rack effect may, if desired, be employed to ensure that the device remains in the position in which it is placed. Alternatively, the moving element 40 of the control devices 10, etc. may be operated by means of a worm or other non-overhauling gear.

While the control elements have been referred to as being manually operated, it will be apparent to those skilled in the art that they may also be actuated by suitable mechanical means for the purpose of producing continued slow motion effects such as sunrise, etc. Due to the advantages of the reversing effect embodied in the invention, it is unnecessary to provide the mechanical devices with any reversing gears, such as are required in the more usual arrangements hitherto used. Likewise, duplication of equipment to furnish the reversing feature is not required.

It will be apparent from the foregoing description that the invention is particularly adapted to make use of a very limited number of standard types of apparatus and is, therefore, economical to manufacture, since a high degree of standardization of the various components is readily possible. At the same time, a wide latitude in respect of various circuits and arrangements is possible, the system of control being capable of considerable flexibility in application to varied circuit requirements without involving additional mechanical features of the manufacture of non-standard apparatus.

While the drawings and description refer to a system of control in three cascaded groups or stages, for example, the grand master, color master and unit control, it will be apparent to those skilled in the art that, without departing from the spirit of the invention, one or more additional cascaded groupings may be provided. For example, in very large installations, in addition to the color masters, there have been used group

masters subject to the color master control and controlling, as a group, a plurality of circuits. It will be obvious that, if the rectifier 7, in the drawings, be considered to be connected, instead of to the reactor 4, to a plurality of reactors similar to 20, each controlling one of a number of control elements 10 in exactly the manner described above, such additional group requirements will be furnished.

It will equally be apparent to those skilled in the art that, in the case of large amounts of power to be controlled in the manner described, there may be employed, within the scope of the invention, three or more stages of rectifiers and reactors instead of the two-stage arrangement consisting of 7 and 9 and 4 and 8, substantially in accordance with the method described in my co-pending application filed June 21, 1933, bearing Serial No. 676,785.

While I have shown and described, by way of example, the method of connecting saturating reactors 20, either in parallel or in series with the control elements 10 as a means of obtaining either direct or inverse control of stage lighting, I wish it to be clearly understood that this feature of my invention is not to be specifically limited to this particular embodiment, but may be used for many other purposes where it is desired to produce two electrical effects varying simultaneously and in opposite sense. For example, means are known to those skilled in the art whereby, due to a variation in the saturating effect applied to a saturating reactor, the phase relation of an alternating current effect, such as, for instance, the voltage applied to the grid of a vapor electric device, may be controlled. It will be obvious to those skilled in the art that, by causing the saturating effect applied to two saturating reactors, in the manner hereinbefore described, to vary in opposite sense, two alternating current grid voltage phase shift effects, varying in opposite directions, may readily be produced.

Having now described the various devices and arrangements which my invention comprises, the operation of the system itself will readily be grasped and easily understood.

The general operation of my invention may be conveniently studied if the procedure, which would be followed by an operator, be briefly outlined.

It will be assumed that an equipment of substantially the scope of Fig. 1, incorporating all of the details shown and described with reference to Fig. 2, is provided. Thus, there will be one grand master 1000, three duplicate sets of color masters 100, i. e., six in all, three of which may be referred to as 100a and three as 100b, connected exactly as shown in Fig. 1 and each having the reversing arrangement, including switches similar to 33a and 33b, as shown in Fig. 2.

Likewise, for each of the illuminating circuits 1, which the system comprises, there will be duplicate control elements 10a and 10b, exactly as shown in Fig. 2.

It may be assumed that the operator is about to present the first two scenes of a performance.

With the all-master switch 32 set in the "off" position, the operator will proceed to set up all of the control elements designated by the suffix a, both color masters and individual control elements, in accordance with the "lighting schedule" for scene one. Any of the color masters which are to be independently controlled will have their switches 190 placed on the upper contacts; those

which are to be jointly controlled by the grand master 1000 will have their switches placed on the lower contacts.

Likewise, all of the individual circuits which are to be independently controlled will be set with the switches 19 on contact 23. Those which are to be group controlled are accumulated on to a color master through contacts 25. Any circuits which are not to be used during the first scene are placed with the switches 19 on contact 24. Each of the control elements 100A and 10A are then turned so as to give exactly the illumination intensity on the various circuits with which the scene is to open. If any of the circuits are required to be operated inversely, the switches 33 are thrown to the right. Otherwise, all of the switches 33 are left in the left-hand position. The operator is now prepared for scene one.

The operator then proceeds to make exactly similar adjustments for the second scene. This he does by setting the control elements 100B and 10B and the switches 190B, 19B and 33b, etc., which are placed in service when the control switch 32 is placed on the lower contact B so as

25 to energize control circuit 31b.

On receiving the prompt signal for the commencement of scene one, the operator closes the all-master switch 32 on to the upper contact A, energizing conductor 31a and picking up all of the relays 26a, both on the individual circuits and on the color masters. The initial illumination set-up, as planned for the commencement of scene one, is now forthwith presented.

During the presentation of the first scene, the operator may make such changes as may be called for by the action of the performance. Any of the individual circuits 1, which are set up for independent control, may be switched on or switched off by the switches 19, as may be desired, or their intensity may be varied by manipulating the control knobs 18. Likewise, any of the circuits which are accumulated on to a color master may be manipulated as a group by operating the appropriate color masters 100 during the scene. If some of the circuits 1 are adjusted for inverse operation by throwing the switch 33 to the right, the lighting of these circuits will go up when the color master is turned down, and vice versa.

50 At the conclusion of scene one, all of the circuits automatically become deenergized when the operator opens switch 32 and leaves it in the "off" position.

When the second scene is to be presented, the operator closes switches 32 on to the lower contact B; and, due to the pre-setting of all of the control elements and switches, the desired intensity of all of the various circuits is immediately provided.

60 The operator makes such changes, during the action of scene two, as is indicated in precisely the same manner as was described in relation to scene one. While he is not so occupied, he proceeds to pre-set scene three. The adjustment of all of the control elements of switches corresponding to the first scene being no longer required, all of the control elements 10 and 100 and switches 19, are now adjusted for scene three. At the conclusion of scene two, the initial lighting arrangement for scene three may immediately follow by throwing the switch 32 back to its upper contact A.

Although I have chosen a particular embodiment of my invention for the purpose of explanation, many modifications thereof will be apparent

to those skilled in the art to which it pertains. My invention, therefore, is not to be limited except insofar as is necessitated by the prior art and the spirit of the appended claims.

What I claim as new and desire to secure by Letters Patent of the United States is:

1. In an illumination control system, a supply circuit, a plurality of adjustable control elements energized from said supply circuit, a plurality of illuminating load circuits each individually controllable by one of said control elements, a further adjustable control element energized from said supply circuit and means for controlling a plurality of said illuminating load circuits simultaneously by means of said further adjustable control element comprising a plurality of saturable core devices, means for applying a variable saturating effect derived from said further control element to all of said saturable core devices simultaneously, and means whereby said saturable core devices cause a variation in the energization of said first-mentioned adjustable control elements.

2. In an illumination control system, a supply circuit, a plurality of adjustable control elements energized from said supply circuit, a plurality of illuminating load circuits, each individually controllable by one of said control elements through means including a saturable core device subjected to a variable saturating effect derived from one of said control elements and having a winding carrying an alternating current variable in accordance with said saturating effect, rectifying means for rectifying said alternating current, and a second saturable core device subjected to a saturating effect due to rectified current derived from the first-mentioned saturable core device, together with a further adjustable control element energized from said supply circuit and means for controlling a plurality of said illuminating load circuits simultaneously by means of said further adjustable control element, comprising a plurality of additional saturable core devices, means for applying a variable saturating effect derived from said further control element to all of said saturable core devices simultaneously, and means whereby said saturable core devices cause a variation in the energization of said first-mentioned adjustable control elements.

3. In an illumination control system, a supply circuit, a plurality of adjustable control elements energized from said supply circuit and furnishing a variable alternating current output, a plurality of illuminating load circuits each individually controlled by one of said control elements through means including rectifying means for rectifying said variable output, a saturable core device subjected to a variable direct current saturating effect derived from one of said control elements and having a winding carrying an alternating current variable in accordance with said direct current saturating effect, rectifying means for rectifying said alternating current and a second saturable core device subjected to a direct current saturating effect due to rectified current derived from the first-mentioned saturable core device, together with a further adjustable control element energized from said supply circuit and furnishing a variable alternating current output, and means for controlling a plurality of said illuminating loads simultaneously by means of said further adjustable control element comprising rectifying means for rectifying said variable output, a plurality of saturable core devices subjected to a direct current saturating effect due

- to rectified current derived from said rectifying means, each having a winding carrying an alternating current variable in accordance with said saturating effect, each of said windings being connected in series with one of said first-mentioned adjustable control elements whereby the energization of said first-mentioned control elements is varied in accordance with the output of said last-mentioned adjustable control element.
4. In an illumination control system, a plurality of illuminating load circuits, a plurality of individual control means for individually controlling the intensity of the illumination of said circuits, means for controlling a plurality of said illuminating circuits simultaneously, comprising at least one group control element, and a plurality of saturable core devices whereby said group control element controls the energization of a plurality of individual control elements, circuit changing means whereby at least one of said illuminating load circuits may be caused to increase and at least one of said illuminating load circuits may be caused to decrease, in intensity of illumination, simultaneously, when said group control element is operated, comprising means for connecting at least one of said saturable core devices in relation to one of said individual control elements so that the energization of said control element is increased when said saturable core device is subjected to increased direct current saturation, and means for connecting at least one of said saturable core devices in relation to one of said individual control elements so that the energization of said control element is decreased when said saturable core device is subjected to increased direct current saturation.
5. In an illumination control system, a plurality of illuminating load circuits, a plurality of individual control means for individually controlling the intensity of the illumination of said circuits, means for controlling a plurality of said illuminating circuits simultaneously, comprising at least one group control element, and a plurality of saturable core devices whereby said group control element controls the energization of a plurality of individual control elements, circuit changing means whereby at least one of said illuminating load circuits may be caused to increase and at least one of said illuminating load circuits may be caused to decrease, in intensity of illumination, simultaneously, when said group control element is operated, comprising means for connecting at least one of said saturable core devices in series with one of said individual control elements so that the energization of said control element is increased when said saturable core device is subjected to increased direct current saturation, and means for connecting at least one of said saturable core devices in parallel with one of said individual control elements so that the energization of said control element is decreased when said saturable core device is subjected to increased direct current saturation.
6. In an electric control system, means whereby a number of power consuming devices may be controlled individually, and means whereby a further number of power consuming devices may be controlled simultaneously, comprising a plurality of saturable core devices, a common direct current saturating circuit embracing all of said saturable core devices, means comprising rectifiers and further saturable core devices whereby the energization of said power consuming devices is controlled, circuit changing means for causing such of said power consuming devices as are to be controlled simultaneously to be controlled in accordance with the saturating effect applied to said saturable core devices having a common direct current saturating circuit, and for causing such of said power consuming devices as are to be controlled individually to be controlled independently of said saturable core devices having said common direct current saturating circuit.
7. In an electric system, means for deriving from a varying electric current a second electric current varying in like manner to the first-mentioned current, and a third electric current varying in opposite sense with respect to the first-mentioned current, comprising a plurality of saturable core devices, means for simultaneously subjecting said devices to like saturating effects, one of said saturable core devices being connected in series with a circuit element and another of said saturable core devices being energized in parallel with another circuit element, whereby energization of the first-mentioned circuit element is increased, and the energization of the second-mentioned circuit element is decreased, when the saturating effect applied to said saturable core devices is increased.
8. In an electric system, means for producing a plurality of electrical effects simultaneously variable in an opposite sense, comprising a plurality of saturable core devices, means for simultaneously subjecting said devices to like saturating effects, one of said saturable core devices being connected effectively in series with a circuit element and another of said saturable core devices being energized effectively in parallel with another circuit element, whereby energization of the first-mentioned circuit element is increased and the energization of the second-mentioned circuit element is decreased when the saturating effect applied to said saturable core device is increased.
9. In an electric system, means for producing a variation in an electrical effect, and means for producing a second electrical effect simultaneously variable in an opposite sense comprising a saturable core device having a winding carrying an alternating current, means whereby the first-mentioned electrical effect causes saturation of said saturable core device, a circuit element connected effectively in parallel with said winding, an electric circuit including said winding and said circuit element in parallel, and means for maintaining a substantially constant current in said circuit, whereby the energization of said circuit element is increased when said first-mentioned electrical effect is decreased and is decreased when said first-mentioned electrical effect is increased.
10. In an electric control system which includes a plurality of power consuming devices each controllable independently through an amplifying system comprising rectifiers and saturable core devices by an individual control element, at least one group control element, and means whereby said group control element may exercise a controlling effect simultaneously on a predetermined number of said power consuming devices, said controlling effect being unaffected by the number of said power consuming devices controlled simultaneously, and the number of said power consuming devices controlled independently, comprising a plurality of saturable core devices, having a common saturating circuit, energized in accordance with the adjustment of

said group control element, and means whereby each of said saturable core devices causes a variation in the energization of one of said individual control elements.

- 5 11. In an illumination control system, a supply circuit, a plurality of saturable core devices each having a saturating winding and an impedance winding, a plurality of adjustable control elements each energized from said supply circuit in series with one of said impedance windings, a plurality of illuminating load circuits each individually controllable by one of said control elements, a further adjustable control element energized from said supply circuit, a circuit variably energized in accordance with the output of said further adjustable control element, said circuit including all of said saturating windings, whereby the energization of each of said first mentioned control elements may be varied simultaneously by said second mentioned adjustable control element.

10 12. In an illumination control system, a supply circuit, a plurality of saturable core devices each having a saturating winding and an impedance winding, a plurality of adjustable control elements each variably energized from said supply circuit in accordance with the impedance of one of said impedance windings, a plurality of illuminating load circuits each individually controllable, through an amplifying system comprising rectifiers and further saturable core devices, by one of said control elements, a further adjustable control element energized from said supply circuit, a circuit variably energized in accordance with the output of said further adjustable control element, said circuit including all of said saturating windings, whereby the energization of each of said first mentioned control elements may be varied simultaneously by said second mentioned control element.

15 13. In an illumination control system, a supply circuit, a plurality of saturable core devices each having a saturating winding and an impedance winding, a plurality of adjustable control elements each energized from said supply circuit in series with one of said impedance windings, a plurality of illuminating load circuits each individually controllable, through an amplifying system comprising rectifiers and further saturable core devices, by one of said control elements, a further adjustable control element energized from said supply circuit, a circuit variably energized in accordance with the output of said further adjustable control element, said circuit including all of said saturating windings, whereby the energization of each of said first mentioned control elements may be varied simultaneously by said second mentioned adjustable control element.

20 14. A system for controlling a plurality of illuminating load circuits in which a predetermined number of said circuits may be controlled independently by means of individual control elements and in which a predetermined number of said load circuits may be controlled collectively by means of a group control element, comprising, a supply circuit, a plurality of saturable core devices each having a saturating winding and an impedance winding, a plurality of adjustable control elements, a plurality of illuminating load circuits each controllable by one of said control elements, circuit changing means for causing the control elements associated with said load circuits which are to be independently controlled, to be energized directly from said supply circuit

25 15. A system for controlling a plurality of illuminating load circuits in which a predetermined number of said circuits may be controlled independently by means of individual control elements and in which a predetermined number of said load circuits may be controlled simultaneously by means of a group control element, comprising a supply circuit, a plurality of saturable core devices each having a saturating winding and an impedance winding, a plurality of adjustable control elements, a plurality of illuminating load circuits each controllable by one of said control elements, a switch associated with each of said control elements, said switch having a first position, in which said control element is energized directly from said supply circuit, and a second position, in which said control element is energized from said supply circuit in series with one of said impedance windings, a further adjustable control element energized from said supply circuit, a circuit variably energized in accordance with the output of said further adjustable control element, said circuit including all of said saturating windings, whereby, when a predetermined number of said switches are placed in said second position, the energization of the control elements associated with said switches may be varied simultaneously by said second mentioned adjustable control element.

30 16. In an illumination control system, a supply circuit, a plurality of adjustable control elements energized from said supply circuit, a plurality of illuminating load circuits each individually controllable by one of said control elements, a further adjustable control element energized from said supply circuit and means for controlling a plurality of said illuminating load circuits simultaneously by means of said further adjustable control element comprising a plurality of saturable core devices, means for applying a variable saturating effect derived from said further control element to all of said saturable core devices simultaneously, and means whereby said saturable core devices cause a variation in the energization of said first-mentioned adjustable control elements, together with a further plurality of adjustable control elements, a plurality of circuit changing means for effectively connecting one of said further adjustable control elements in place of one of said first-mentioned adjustable control elements, and means for operating a plurality of said circuit changing means simultaneously, for pre-setting a lighting effect.

35 17. In an illumination control system, a supply circuit, a plurality of adjustable control elements energized from said supply circuit, a plurality of illuminating load circuits each individually controllable by one of said control elements, a further adjustable control element energized from said supply circuit and means for controlling a plurality of said illuminating load circuits simul-

aneously by means of said further adjustable control element comprising a plurality of saturable core devices, means for applying a variable saturating effect derived from said further control element to all of said saturable core devices simultaneously, and means whereby said saturable core devices cause a variation in the energization of said first-mentioned adjustable control elements, at least two control elements being provided for each control function, together with means for pre-selecting in advance of the pres-

entation of an illuminating effect, the circuits to be utilized in producing the said effect, the circuits which are to be controlled individually, the circuits to be accumulated under a group control, said group controlled circuits which are to be controlled directly, said group controlled circuits which are to be controlled inversely, and the intensity of illumination to be provided by each of said circuits.
